(57) **CLAIM**

The ornamental design for a display screen with a transitional graphical user interface for an emergency resource request software, as shown and described.

DESCRIPTION

FIG. 1 is a front view of a first image of a display screen with a transitional graphical user interface for an emergency resource request software;

FIG. 2 is a front view of a second image thereof;

FIG. 3 is a front view of a third image thereof;

FIG. 4 is a front view of a fourth image thereof;

FIG. 5 is a front view of a fifth image thereof, comprising solidly shaded areas that are part of the claimed design;

FIG. 6 is a front view of a sixth image thereof, comprising solidly shaded areas that are part of the claimed design;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof; and,

FIG. 12 is a front view of a twelfth image thereof.

The broken lines in the drawings depict portions of the display screen that form no part of the claimed design.

The appearance of the transitional image sequentially transitions between the images shown in FIGS. 1-12. The process or period in which one image transitions to another image forms no part of the claimed design.

The image shows a user interface for a mobile application named 'CORE connect'. At the top, there is a back arrow and the app's logo. The main title 'Let's get some information.' is displayed in a large, bold, sans-serif font. Below the title, a sub-instruction 'Please fill out as much information as you are able at this time.' is shown. The form consists of several input fields with labels: 'First Name' (with a large input box), 'Last Name' (with a large input box), 'Phone Number' (with a box containing '()'), 'Email' (with a large input box), and 'Preferred Method of Contact' (with two radio button options: 'Phone' and 'Email'). Below these is a section for 'Reason for visiting or interests' with three radio button options: 'Business', 'Personal', and 'Social'. At the bottom, there is a large, rounded rectangular button labeled 'Continue'.

Let's get some information.

Please fill out as much information as you are able at this time.
